EGG TRAY

Maurice H. Freeman, Henderson, Ky., assignor to Tri-State Plastic Molding Company, Henderson, Ky., a corporation of Kentucky

Filed July 24, 1961, Ser. No. 66,025

Term of patent 3½ years

(Cl. D58—13)

FIG. 1.

FIG. 2.

FIG. 1 is a top plan view of an egg tray embodying my new design;

FIG. 2 is an end elevation view thereof;

FIG. 3 is a side elevation view thereof;

FIG. 4 is a bottom perspective view thereof; and

FIG. 5 is a top perspective view thereof.

I claim:

The ornamental design for egg tray, substantially as shown.
